(57) **CLAIM**

The ornamental design for the hooked-up cart apparatus as shown.

DESCRIPTION

FIG. 1 is a front elevational view of the hooked-up cart apparatus.

FIG. 2 is a front perspective of the hooked-up cart apparatus.

FIG. 3 is a rear perspective of the hooked-up cart apparatus.

FIG. 4 is a right perspective of the hooked-up cart apparatus.

FIG. 5 is a left perspective of the hooked-up cart apparatus.

FIG. 6 is a top plan of the hooked-up cart apparatus.

FIG. 7 is a bottom plan of the hooked-up cart apparatus.

FIG. 8 is a front elevational view of the hooked-up cart apparatus showing one fixed arrangement of the movable cylindrical rod holders when in use; and,

FIG. 9 is a front elevational view of the hooked-up cart apparatus showing an alternative fixed arrangement of the movable cylindrical rod holders when in use.
